UNITED STATES PATENT OFFICE.

ALFONS SCHAEFER, OF BROOKLYN, NEW YORK.

AIRSHIP.

Application filed July 12, 1928. Serial No. 292,161.

This invention relates to aircraft and more particularly to craft of the lighter than air type.

Persons skilled in the art have advanced the opinion that the commercial success of aviation ultimately depends upon the "lighter than air" type of craft for the reason that the carrying capacity of the usual airplane is so limited as to render the heavier than air machine impractical for wide use. Also, the lighter than air machine is safer and inasmuch as safety is the predominating factor in aviation, engineers are developing lighter than air machines which embody many of the principles of the airplane.

It is therefore an object of this invention to provide a lighter than air machine which is safer than the heavier than air machine of the same power and at the same time has greater carrying capacity.

A further object is the provision of a flying machine with an enclosed engine.

These and other objects are attained by the novel construction, combination and arrangement of parts, hereinafter described and shown in the accompanying drawing, constituting a material part of this disclosure, and in which:—

Figure 1 is a side view of the flying machine.

Figure 2 is a longitudinal sectional view of the machine.

Figure 3 is a sectional view taken on line 3—3 of Figure 2.

Referring to the drawings, the flying machine is shown to have a plurality of longitudinal ribs 4, preferably made from a light metal. These ribs are joined at the forward end of the machine by a nose plate 5 and the forward section is covered by thin sheet metal 5', while the rear end of the ribs 4 are joined by a nose 6 and the rear section covered by metal 6'.

Several of the upper ribs 4 are bent at 7 to form a cabin to accommodate the seat 8 and various control devices, (not shown), while the metal sheet 5' is deflected upward to form a windshield 9.

Adjacent the tail 10 and encompassed by the ribs 4 is a gas tight chamber 11 which is filled with a gas having a specific gravity less than air. A similar chamber 12, in the forward end of the machine is also filled with such a gas.

In the rear of the seat 8 is a partition 13 which sets off a compartment 14 beneath the

seat in which baggage and other things may be stored.

In the rear of partition 13 is mounted the engine 15 having a propeller 16, the engine 60 being covered by a metal sheet 17 which has a plurality of conical portions 18 open at their bases.

In operation air passes through the conical portions 18 to the propeller 16 and is deflected outwardly by the conical nose 20, which is mounted on the wall 19.

From the above description it will be seen that there has been provided a flying machine which is lighter than air, consequently safer 70 than the usual heavier than air machine and in which the motor is protected from rain, snow and other elements disadvantageous to its proper operation. The machine herein disclosed has a greater carrying capacity than 75 the usual airplane, and a less powerful motor may be used, since the motor is used only for the purpose of driving the machine forward.

The foregoing disclosure is to be regarded as descriptive and illustrative only and not 80 as restrictive or limitative of the invention, of which obviously an embodiment may be constructed, including many modifications, without departing from the general scope herein indicated and denoted in the appended 85 claims.

Having thus described my invention, what I claim as new and desire to secure by Letters Patent, is:—

1. An airship comprising a frame having 90 a plurality of longitudinal metal ribs, chambers mounted in the forward and rear ends of the frame, said chambers being filled with a gas having a specific gravity less than air, an engine mounted within the frame and cov- 95 ered by a metal sheet, said metal sheet having open conical portions through which air may be directed to the propeller of the engine, and a conical nose mounted in the frame immediately behind the propeller to deflect 100 the air outwardly after it has passed the propeller.

2. A flying machine comprising a frame having a plurality of metal ribs, chambers filled with a gas of less specific gravity than 105 air mounted in the frame, partitions in the frame to form a compartment for carrying baggage, an engine mounted behind said compartment, means to direct air to the propeller of the engine, and a conical nose adjacent the 110 propeller to deflect the air outwardly after it has passed the said propeller.

3. A flying machine comprising a frame of light metal having a plurality of longitudinal ribs, several of the upper ribs being bent to form a passenger cabin, partitions in the frame to provide a baggage carrying compartment, chambers filled with a gas of less specific gravity than air mounted in the

forward and rear ends of the frame, and means to control the path of air to and from the propeller of the engine.

10 In witness whereof I have affixed my signature.

ALFONS SCHAEFER.
